UNITED STATES PATENT OFFICE.

CHARLES P. MADSEN, OF CHICAGO, ILLINOIS, ASSIGNOR TO THE MICHIGAN STOVE COMPANY, A CORPORATION OF MICHIGAN.

ARMORED ELECTRIC HEATING-UNIT.

1,093,792.

Specification of Letters Patent. Patented Apr. 21, 1914.

Application filed February 3, 1913. Serial No. 745,936.

To all whom it may concern:

Be it known that I, CHARLES P. MADSEN, a citizen of the United States of America, and a resident of Chicago, county of Cook, 5 and State of Illinois, have invented certain new and useful Improvements in Armored Electric Heating-Units, of which the following is a specification.

The main objects of this invention are to 10 provide an improved construction for electric heating units; to provide improved and more efficient and durable means for protecting such units against electrical and mechanical injury; to provide an improved 15 form of armor for the heating element; to provide improved terminal structures for connecting such units to the source of current; to provide improved means for protecting the terminal connections from being 20 short-circuited by liquid spilled thereon, or from contact with other articles likely to cause either a short-circuit or mechanical injury thereto; to provide an armored electric heating unit which will operate at a 25 higher emissivity rate; and to provide a composite flexible dielectric medium suitable for high temperature conditions.

What is herein meant by an "armored" unit is one in which the heat generating conductor is protected against mechanical injury from jolts, blows or contact with external objects, and also against any accidental electrical contacts or short-circuits, although permitting the ready transfer and 35 radiation of heat energy. A suitable armor for this purpose is one which is externally of such character as to be able to resist distortion and injury through contact with external objects, and which is internally of 40 such character as to have good insulating properties and at the same time be capable of keeping moisture and air away from the heat generating conductor.

As far as I am aware no single substance 45 has yet been found which would not become a conductor of electricity when exposed to moisture or upon temperature rising, excepting those substances which are brittle and therefore unsuitable in themselves to 50 fully comply with the before mentioned conditions. Therefore, armored units are, in present practice, of composite structure being made up of a layer of electrical insulation having high thermal conductivity and 55 an outer metallic shell.

The chief difficulties in constructing such a unit have been to make such composite structure which will remain mechanically solid and moisture proof through expansion and contraction due to temperature changes, 60 and to provide a terminal structure which will be practically proof against short-circuiting by the spilling of liquids on the unit and which will withstand the same or a higher temperature than the unit itself. 65

A construction accomplishing the foregoing objects and avoiding the difficulties referred to may be made according to the present invention, a specific embodiment of which is illustrated in the accompanying 70 drawings, in which:

Figure 1 is a perspective view of a heating element and means for protecting the same and its terminals, especially arranged for use in an oven or broiler. Fig. 2 is a 75 plan view of one end of the broiler with the heating units in place and showing a part of the mounting broken away to show one of the unit terminals. Fig. 3 is a front elevation of the heating element shown in Fig. 1 80 and shows the terminal and housing structure used in connection therewith. Fig. 4 is a detail of the core which supports the winding of the heating element. Fig. 5 is a 85 detail showing the manner in which the winding is applied to the core. Fig. 6 illustrates the manner of applying the terminal sleeves by means of which connection is made to an external source of current. Fig. 7 illustrates the innermost layer of insulation material. Fig. 8 is a similar view showing the same coated with an application of powdered insulating material or paste which fills the spaces between the armor and the other insulation, as well as all interstices in 90 the latter. Fig. 9 is a detail of one of the hard, thin, smooth strips which are used to protect the layer of powder and enable the assembled internal parts of the unit to be inserted easily into the armor. Fig. 10 is a 100 detail of the tubular metal casing which protects the insulation against external injury and moisture. Fig. 11 is a broken perspective view showing the relative positions of the various parts of the unit in their assembled relation, the armor being omitted in this view. Fig. 12 is a longitudinal section of the same. Fig. 13 is a perspective view of the heating unit, the same being shown 105 without its terminal connections. Fig. 14 is 110

an enlarged sectional view of the heating unit as shown in Fig. 12. Fig. 15 is a detail of a modified terminal arrangement adapted for use with long units.

- 5 In the construction shown, the high resistance conductor 1, which makes up the heating element proper, is in the form of a flat wire or ribbon wound in some of the usual ways as, for example, on a core 2 of 70
10 insulating material, as for instance mica, and the terminal end portions 3 of the conductors 1 are then bent outwardly so as to extend lengthwise beyond the ends of the winding. Notches 4 may be formed in the 75
15 core at the ends of the winding to facilitate turning the terminals outward toward the ends of the core.

Practically all of the difficulties usually encountered in making durable terminal connections with windings of high temperature alloys, such as are usually used in heating elements are overcome by providing thin metallic shields 5 in the form of wrappings or flattened tubes applied to the ends of the 80
20 core and engaging the ends of the wire and forming enlarged extensions thereof. These sleeves, when in place, are flattened under great pressure, so as to make good electrical contact with the wire, which extends into 85
25 the tubes to make large contact therewith. The portions of the conductor within the terminal tubes, therefore, divide the current with the terminal tubes, and since the resistance of the conductor ribbon is relatively 90
30 high compared with that of the tubes, the former, where in contact with the shields, would carry practically no current if the contact were perfect. On account of the relatively greater conductivity of the combined 95
35 tube and conductor at this point, the terminal portions of the conductor will be kept at comparatively low temperature. Should, however, the electrical contact between the conductor and the tube become imperfect for 100
40 any reason, the increased local resistance at this point might tend to cause the connection to become highly heated, but nevertheless it is practically impossible for it to burn out since it is protected from air by the sleeve, 105
45 and the temperature would be kept relatively low on account of the heat which would be carried away from it by the tube 5 and the terminal mounting.

The next step in the process of assembling 50
55 the unit illustrated consists of covering the heating element with a suitable insulator to protect it from being short-circuited by its armor. This insulation, in the form shown, consists of a wrapping 6 of asbestos paper, 110
60 preferably a ribbon of the paper, wound spirally from end to end of the element, the ends of the asbestos strip being fastened temporarily by strings 7 or other suitable means as illustrated in Fig. 7. The insulation is further improved by filling and coat- 115

ing the paper with a hard comparatively infusible finely pulverized substance 8 preferably silica, which increases both the electric insulating strength and the heat conductivity of the asbestos wrapping.

In order to prevent displacement of the powder, and to otherwise facilitate the insertion of the heating element into the armor tube, two strips 9 of continuous hard, thin, smooth, non-conducting material such as 120
55 mica are fastened to opposite sides of the element, as illustrated in Fig. 11, these being cut to the form shown in Fig. 9 so as to completely cover both faces of the portion of the element which is inclosed in the armor. The 125
60 extremities of the strips 9 are secured by metal armor segments or shields 10, which may be made of strips wrapped around the parts or may be made of flattened tubes. It 130
65 will be noted from Figs. 11 and 12 that the sleeves 10 and the mica strips 9 terminate a considerable distance inward of the perforated ends of the sleeves 5. The middle segment of the armor is a flattened tube 11 which snugly fits the heater unit parts when 135
70 assembled, as in Fig. 12, and is slipped over these parts to a middle position, as illustrated in Figs. 12 and 13. The lower portion of the tube 11, which is shown inverted in Fig. 14, is somewhat shorter in length than the 140
75 upper portion so that the top portion slightly overhangs the ends of the sleeves 10. The inner parts of the assembled element are now bent downward at 12 adjacent to the 145
80 ends of the tube 11. The extremities of the sleeves 5 preferably, but not necessarily, are then bent to a horizontal position in the 150
85 same plane with each other, as illustrated in Figs. 12 and 13. This offsetting of the 155
90 ends of the heating element and the corresponding joints in the armor, allow for longitudinal expansion and contraction of the 160
95 various parts without causing rupture or distortion of the unit or its armor. The 165
100 terminal end portions of the sleeves 5 are 110
105 preferably perforated for receiving a screw or the like, and may be secured to rigid binding posts. On account of the peculiar longitudinal form of the element the joint with the binding posts will be unaffected by 115
110 expansion and contraction of the element. After the parts are assembled, as shown, the tube 11 is subjected to great pressure 120
115 tending to further flatten it, and thereby causing it to exert a permanent pressure on 125
120 the heating element and its insulation, thus increasing the thermal conductivity of the latter. By reason of the fact that the tube 11 is seamless or substantially integral on 130
125 all sides, no amount of contraction and expansion under temperature changes can cause it to become distorted or to open up so as to admit moisture through its walls. Even though there be differences in the 135
140 expansibility of the various parts under tem- 145

perature changes, the permanent set which is given to the tube 11 in the final flattening will offset such difference in expansion to a sufficient extent to prevent the tube from becoming loosened and thus providing space for the entrance of moisture.

The downwardly inclined terminal armor sections 10 are made of relatively thin material and are preferably telescoped slightly within the ends of the heavier middle armor section 11 in assembling. Then when the ends of the element projecting from the section 11 are bent down the inner ends of section 10 are also bent correspondingly, thus providing a most secure and efficient joint.

In the form shown the terminal connections on opposite sides of the heater respectively are inclosed, each set within a metallic casing which forms an extension of the armor tubes 11, as illustrated in Figs. 1 and 2. In these views numeral 15 designates a trough-shaped casing shell or housing member which is formed of such length as to inclose either one or a series of terminals, depending on the size of heater desired. A covering 16 of suitable shape closes the upper end of the member 15 and completes the housing. It is to be noted that the covering 16 overhangs the sides of the trough 15 and slopes downward at all sides, so as to shed any liquid which might be spilled on it, and that the armor tube 11 extends into a suitable opening in the side of the cover fitting snugly in said opening so as to avoid as much as possible the leakage of liquid into the housing. Any liquid which might leak in would run down along the inclined sleeve 10 and would not tend to enter the interior of the armor 11. The binding post 17 is thoroughly insulated from the walls of the housing, as shown, and the bottom of the housing is pressed up in the vicinity of the binding post, so that any liquid leaking into the housing would be deflected from the binding post and thereby the likelihood of such liquid short-circuiting the series of binding posts would be avoided. Fitting into such upward pressed portion is a corresponding upward pressed portion in the oven floor 18 upon which the housings 15 are mounted. The binding posts 17 with their nuts and washers hold the floor and housings closely together so that liquids spilled upon the floor 18 cannot leak through into the housing or through the floor into the connection of the electric supply wire 19 to the lower end of the binding post 17.

The hereinbefore described construction is well adapted to heating units of short length, say up to six or eight inches in length, but in places where it is desired to have units of considerably greater length it is preferred to modify the terminal construction as illustrated in Fig. 15. In this

case the ends of the armor 11 are not undercut and the flexible armor 10 is omitted since the armor 11 extends into the side of the terminal housing 15. In order to allow for the greater degree of expansion and contraction which would arise in a long unit, the terminals 5 of the heating element are offset by abrupt 90° bends. This gives great flexibility and allows for all of the required expansion and contraction without exerting strains which would tend to loosen up the connection of the element to the binding post 17.

Although but one specific embodiment of my invention is herein shown and described, it is to be understood that various details of construction may be changed somewhat or omitted without departing from the spirit of my invention as defined in the following claims.

I claim:

1. An electric heating unit comprising a heating element, a covering of porous insulating fabric therefor, a thin filling of powdered insulating material applied to the latter, and a close fitting metallic armor tightly inclosing and compressing the same, said powdered material filling all the minute spaces between said heating element, insulation and armor, and filling the pores or interstices of said insulation.

2. An electric heating unit, comprising a flat core of insulating material, a winding of high resistance conducting material mounted on said core, a wrapping of insulating material inclosing said winding, a pair of strips of comparatively stiff material longitudinally disposed and secured to opposite flat sides of said wrapping of insulating material, and a flat tubular shell tightly holding and compressing said parts and serving as an armor therefor.

3. A heating unit, comprising a heating element having a thin fibrous fireproof insulating covering permeated with a powdered refractory insulating material.

4. A heating unit, comprising a coil of resistance material covered with a wrapping of fibrous fireproof insulating material, said wrapping being permeated and covered by a continuous layer of powdered refractory insulating material.

5. A heating unit, comprising a coil of resistance material covered with a wrapping of fibrous fireproof insulating material, said wrapping being covered by a continuous layer of powdered silica.

6. A heating unit, comprising a coil of resistance material covered with a wrapping of fibrous fireproof insulating material, said wrapping being covered by a continuous layer of powdered insulating material adapted on being heated to form an air tight seal for the heating element.

7. A heating unit, comprising a coil of

1. A resistance material covered with a wrapping of fibrous insulating material, said wrapping being covered by a continuous layer of powdered refractory insulating material and an open-ended armor of comparatively rigid material adapted to be slipped endwise over and inclose the whole, there being also a layer of comparatively hard and smooth insulating material extending along the exposed surfaces of said layer of powdered material and adapted to protect the powder when the coil is being inserted into said armor.
2. A heating unit, comprising a core of insulating material, a winding of resistance material thereon, a wrapping of flexible insulating material inclosing said winding, a layer of powdered insulating material surrounding said wrapping, sheets of mica secured against the outside of said layer of powdered material, metal sleeves confining the ends of said mica strips, and a tubular armor inclosing the parts between said sleeves.
3. A heating unit, comprising a core of insulating material, a winding of resistance material thereon, a wrapping of flexible insulating material inclosing said winding, a layer of powdered insulating material surrounding said wrapping, strips of mica secured against the outside of said layer of powdered material, metal sleeves confining the ends of said strips, and a substantially seamless tubular armor inclosing the parts between said sleeves and overlapping the latter.
4. In an electric heating apparatus, the combination of a flat tubular armor, an insulated heating element extending through the same and having electric terminal end portions projecting beyond the ends thereof, said terminal end portions being downwardly offset out of the plane of said tubular armor, binding posts securing said terminal end portions, and a housing at each end inclosing said binding posts and forming substantially a continuation of said armor at each end thereof, said housings having their bottom walls perforated to receive said binding posts, and the perforated portions thereof being formed upwardly out of the plane of the bottom of said housings and the top of said housings overlapping said armor, all being arranged to prevent short-circuiting of said terminals by liquid spilled on said armor.
5. An electric heating unit, comprising a core of insulating material, a winding of resistance wire thereon, flattened sleeves fitting over the ends of said core in intimate contact with the ends of the winding and adapted to serve as enlarged terminals therefor, insulation covering said winding and the adjacent ends of said sleeves, and an armor surrounding said insulated parts and being made up of overlapping tubular segments disposed at an angle to each other.
6. An electric heating unit comprising a core of insulating material, a winding of resistance wire thereon, flattened sleeves fitting over the ends of said core in intimate contact with the ends of the winding and adapted to serve as enlarged terminals therefor, insulation covering said winding and the adjacent ends of said sleeves, said sleeves being bent to offset the outer extremities thereof from the plane of the winding, and an armor surrounding said insulated parts and being made up of overlapping tubular segments and meeting at the bends in said sleeves.
7. In a device of the class described, a horizontally disposed floor plate, in combination with an armored heating element having supporting end terminals bent downwardly and secured by insulating means to said floor plate to uphold and support the heating element suitably spaced apart from said plate, substantially as and for the purpose set forth.
8. An armored heating element having a rigid central body armor, and a flexible armor extending beyond the rigid armor to allow for bending the ends of the said element into another plane and still be protected at the bent portion.
9. An armored heating element having a resistance element, insulation therefor, a rigid central armor, and a flexible armor projecting beyond the rigid armor, the resistance element and insulating material extending beyond the flexible armor.
10. An armored heating element arranged to mount on terminal posts and having a rigid body armor, and a flexible projecting armor portion bent so that the expanding of the element by heat may be compensated for without moving the ends in contact with the terminal posts.
11. In a device of the class described, an electric heating element in combination with a protective housing arranged to receive a terminal of said heating element, a floor element upon which said housing is mounted, and a binding post for supporting said terminal within the housing and arranged to securely hold said housing in place upon said floor element.
12. In a device of the class described, a heating element in combination with a terminal housing formed to receive a terminal of said heating element, and a binding post arranged to project upward into said housing through its bottom and insulated therefrom to support said terminal, said bottom being somewhat elevated around the said binding post to deflect moisture therefrom and the roof of said housing being arranged to deflect moisture.
13. In a device of the class described, a

floor element and a terminal housing mounted thereon in combination with an insulated binding post projecting upward through registering perforations in the floor and the 5 base of said housing to support a terminal therein, said floor and base being raised at and adjacent to the point of entry of the said binding post to deflect moisture from the insulated post and to prevent entrance

of moisture spilled upon the said floor element.

Signed at Chicago this 11th day of January 1913.
